UNITED STATES PATENT OFFICE.

CHARLES F. HOGUE, OF CUNNINGHAM, KANSAS.

DESIGN FOR A GATE.

49,388.

Specification for Design. Patented July 18, 1916.

Application filed October 23, 1915. Serial No. 57,619. Term of patent 7 years.

To all whom it may concern:

Be it known that I, CHARLES F. HOGUE, a citizen of the United States, residing at Cunningham, in the county of Kingman and State of Kansas, have invented a new, original, and ornamental Design for Gates, of which the following is a specification, reference being had to the accompanying drawing, forming part thereof.

The figure is an elevation of a gate, showing my new design.

I claim:

The ornamental design for a gate, as shown.

CHARLES F. HOGUE.

Witnesses:

R. W. HART,
RALPH ST. AUBYN.
